Continuation-in-part of abandoned design application Ser.
No. 199,829, Nov. 17, 1971. This application Jan. 18,
1974, Ser. No. 434,413

Term of patent 14 years

Int. Cl. D19—06

U.S. Cl. D10—62

FIG. 1 is a front elevational view of a microfont lettering guide showing my new design;

FIG. 2 is a rear elevational view thereof;

FIG. 3 shows both a top plan view and a bottom plan view thereof;

FIG. 4 is an end elevational view thereof; and

FIG. 5 is an elevational view thereof in cross section along the line of and in the direction of arrows 5 in FIG. 1.

This is a continuation-in-part of application Ser. No. 199,829, filed Nov. 17, 1971, now abandoned.

I claim:

The ornamental design for a microfont lettering guide, as shown and described.
